UNITED STATES PATENT OFFICE.

EMBURY McLEAN, OF BROOKLYN, NEW YORK.

PRESSURE-REGULATING APPARATUS.

1,071,771.

Specification of Letters Patent. Patented Sept. 2, 1913.

Application filed July 10, 1907. Serial No. 383,062.

To all whom it may concern:

Be it known that I, EMBURY McLEAN, a citizen of the United States, and a resident of Brooklyn, borough of Brooklyn, in the county of Kings and State of New York, have invented certain new and useful Improvements in Pressure-Regulating Apparatus, of which the following is a specification.

This invention relates to pressure-regulating means, and in the present instance, I have shown the same as employed in conjunction with a furnace for controlling the pressure of gases therein. This, however, is merely to illustrate one use of the invention, and I do not confine myself to this specific use as the invention may be employed for other purposes, such as the regulation of pressure in a steam boiler, which is one of a battery of boilers supplying steam into a common head or pipe, by the difference in pressure between the boiler and the header. Such a use is shown and claimed in my co-pending application filed as of even date hereof.

The invention consists in the construction, combination and arrangement of parts set forth in and falling within the scope of the appended claims.

In the accompanying drawings wherein like characters of reference indicate like parts in all the views, Figure 1 is a side view partly in section of a steam boiler furnace equipped with my invention, such view showing a deflecting plate regulator controlling the damper in the chimney outlet to the boiler furnace, and the means by which the deflection of the plate controls the position of the damper; Fig. 2 is an enlarged, detail sectional view of the deflecting plate. Fig. 3 is an enlarged detail sectional view of another form of deflecting plate provided with means for resisting the motion of said plate, and means for adjusting said resistance; Fig. 4 is an enlarged detail view of the deflecting plate mounted on an axis other than the horizontal; in this instance, on a vertical axis.

First referring to the invention as illustrated in Figs. 1 and 2 I will now describe the same in detail. A indicates a furnace and B a boiler operated by the furnace. C is a blower supplying air to the furnace. D is the chimney connection of the furnace and E a damper therein. F indicates as an entirety the deflecting plate regulator located

in the opening G in the wall of the furnace, making communication between the interior of the furnace and the outside of the latter. H is a valve operated by the motion of the plate F by means of the connecting rods f and h. The valve H controls the opening of the supply pipe S connected with any suitable source of fluid pressure, and the waste pipe W leading from the valve casing to any point of discharge. I is a motor comprising a cylindrical casing i and a piston i² which controls the motion of the rod i³. The pipe i⁴ connects the motor casing below the piston with the chamber of the valve H. A weight i⁵ is secured to the rod i³ and the chain i⁶ connects the motor to the damper lever e of the damper E, the weight e² being so arranged that it opens the damper when the chain slackens due to the rising of the piston i². In these Figs. 1 and 2 the deflecting plate regulator F as shown, is constructed as follows: The plate F, which is of any suitable material, is supported in any suitable manner on the axis f' which is below the center of gravity, the plate having a greater area on one side of the axis than on the other—in this case the axis being at the edge of the plate—the entire area is on one side. In this instance the method of support shown is a knife edge socketed in the bearing f², the rod f being connected to the plate and to the valve rod h as heretofore described. Under these conditions the plate is in an unstable condition of equilibrium and will rest against one or the other of the stops f³ and f⁴.

The operation is as follows: If the pressure on the furnace side of the opening G is greater than the pressure on the other side of the plate, the latter will be deflected to the stop f⁴, and, vice versa, if the outside pressure is greater than the pressure in the furnace, such plate will be deflected in the stop f³. In the first condition the valve H shown in Fig. 1 will assume a position whereby the supply pipe S is open to the motor I and the piston i² will be raised, thus slackening the chain and permitting the damper to open, thereby reducing the pressure in the furnace chamber. When this pressure becomes lower than the outside pressure the deflecting plate regulator F will be moved to the position where it rests against the stop f³, thereby moving the valve H to a position where the supply pipe S is closed and the vent or waste pipe W is opened to

the motor I, so that the fluid pressure in the motor cylinder is relieved through the pipe i^4 and the pipe W. The weight i^5 lowers the piston i^2 and the chain i^6 moves the damper 5 toward its closed position. Under these conditions the pressure in the furnace increases until it becomes greater than the outside pressure, and the deflecting plate regulator F is moved to the stop f^4 when 10 the reverse operation heretofore described takes place. It will thus be seen that my pressure regulator will maintain substantially the pressure inside the furnace as exists outside thereof.

15 I have shown one means of controlling the pressure in the chamber of the furnace A, namely, by the movement of the damper E in the chimney connection D to the furnace. A similar mechanism might be employed to control the speed of an exhaust fan connected with D, by having the chain i^6 operate the steam valve of the engine driving the exhaust frame. Similarly the 20 same mechanism might be used to control the speed of the blower C supplying air to the furnace. Or, it could be used to control a damper in the air duct c. In all of these instances when properly adjusted the regulator would maintain the same pressure in 25 the furnace chamber as exists outside.

Referring to the modification shown in Fig. 3 the deflecting plate F is mounted on an axis f^{10} which may be through or below its center of gravity. In this figure it is 30 shown as passing through the center of gravity of the plate. The enlarged portion of the plate f^{11} below the axis f^{10} is equal in weight to the portion of the plate above such axis, but the area of the plate below 35 the axis is much smaller than the area above such axis. The plate is connected in the manner heretofore described, with a valve H. f^{12} is a spring acting to oppose the motion of the plate F and f^{13} and f^{14} are adjustable 40 screw rods for regulating the resistance offered by the spring to the motion of the plate. In this case manifestly any desired 45 pressure can be maintained inside the furnace, either greater or less than the outside 50 pressure.

In Fig. 4 the plate is shown as mounted on an axis other than horizontal and in the case shown is mounted on a vertical axis, preferably through the center of gravity, 55 such plate having a greater area on one side of the axis than on the other. The operation is the same as that of the plate shown in Fig. 3.

In Figs. 2 and 3 the deflecting plate regulator F is shown with the flanges f^{15} and f^{16} which closely approach the wall f^{17} of the opening G. The purpose of these flanges is to form an elongated restricted space between the plate and the edge of the furnace 60 wall opening to restrict the flow of fluid

through the opening between the plate and wall and thereby obtain more sensitive action of the regulator.

Having thus described my invention, what I claim as new and desire to secure by Letters Patent, is:

1. The combination of a chamber having an opening therein, of a regulating plate located at said opening, said plate being operated upon on one side by the pressure within the chamber and at the opposite side by the pressure outside the chamber, such plate being pivotally supported on an axis through its center of gravity and having a greater area on one side of its axis than on the other, means for returning the plate to neutral position, and means controlled by the motion of the swinging plate to regulate the pressure within the chamber.

2. The combination with a chamber having an opening therein having a side wall, a swinging plate regulator located within said opening and movable through the same, and acted upon by the fluid pressures on opposite sides thereof, means for resisting the deflecting motion of the plate, and means controlled by the motion of the plate to regulate the pressure at the opening, and means at the edge of the plate cooperating with said side wall the opening forming and maintaining an elongated restricted space to resist the flow of fluid between the plate and the edge of said opening.

3. The combination with a chamber having a passageway therein, of a swinging plate supported on an axis through its center of gravity and adapted to be acted upon by the pressure inside the chamber, the pivot for said plate being located adjacent the base of said opening, and the part of the plate subjected to the pressure extending upward from the pivot to a point adjacent the top of the opening, and means controlled by the plate for regulating the pressure within the opening.

4. The combination of a chamber having an opening therein, a swinging regulating plate located within said opening and conforming thereto and movable through the opening, and a flange in said plate co-operating with the edge of the opening during the movement of the plate to maintain a restricted space when the plate swings on its fulcrum.

5. The combination of a chamber having an opening therein, a swinging regulating plate located at said opening and conforming thereto, and oppositely extending flanges on said plate at right-angles to the plane of the latter and arranged to co-operate with the edge of the opening to maintain a restricted space between the plate and the edge of the opening when the plate swings on its fulcrum.

6. In a regulating apparatus in combina-

tion, a chamber wall having an opening, a regulating plate pivoted in said opening, said plate being operated upon one side by the pressure within the chamber and on the opposite side by the pressure outside the chamber, such plate being supported to swing on an axis approximately through its center of gravity, and having a greater area on one side of its axis than on the other, means other than gravity tending to bring the plate to a neutral position, and means controlled by the motion of the swinging plate to regulate the pressure within the chamber.

15 7. In a regulating apparatus in combination, a chamber wall having an opening, a regulating plate pivoted in said opening, said plate being operated upon one side by the pressure within the chamber and on the opposite side by the pressure outside the chamber, such plate being supported to swing on an axis approximately through its center of gravity, and having a greater area on one side of its axis than on the other, a spring tending to bring the plate to a neutral position, and means controlled by the motion of the swinging plate to regulate the pressure within the chamber.

8. The combination of a chamber having an opening therein, a swinging regulating plate located within said opening and movable through the same, said plate being operated upon one face by the pressure outside the chamber and on the opposite face by the pressure inside the chamber to move the plate, and means for so movably supporting the regulating plate that an excess of

pressure acting on one side of the plate does not have to overcome the action of gravity in order to move the plate.

40

9. The combination of a chamber having an opening therein, a swinging regulating plate located within said opening and movable through the same, said plate being operated upon on one face by the pressure outside the chamber and on the opposite face by the pressure inside the chamber to move the plate, and means for so movably supporting the plate that the excess of pressures acting on one side of the plate does not have to overcome the action of gravity in order to move the plate, said plate having a flange forming with a wall of the opening a restricted clearance space during the movement of the plate to retard the flow of fluid through said clearance.

45

10. Means for regulating furnaces, in combination with a furnace wall having an opening, a swinging plate mounted in said opening and movable through the same, and exposed on its opposite faces to pressure inside and outside the furnace wall, means for so movably supporting said plate that the excess of pressure on one face does not have to overcome the action of gravity to swing the plate, and means operable by the plate to regulate the furnace.

50

In testimony whereof I have signed my name to this specification in the presence of two subscribing witnesses.
